HENRY A. HOUSE, OF BRIDGEPORT, CONNECTICUT.

KNOCKDOWN METAL BARREL

1,078,621.

Specification of Letters Patent. Patented Nov. 18, 1913.

Application filed January 6, 1910. Serial No. 536,728.

To all whom it may concern:

Be it known that I, HENRY A. HOUSE, a citizen of the United States, and a resident of Bridgeport, in the county of Fairfield and State of Connecticut, have invented certain new and useful Improvements in Knockdown Metal Barrels, of which the following is a specification.

My invention relates to knock-down hoopless metal barrels, and it is constructed with interlocking sliding staves and overlaps and interlocking heads.

To enable others to understand my invention, reference is had to the accompanying drawings, in which:

Figure 1 is a perspective view of my improved metal barrel; Fig. 2 a detail view of one of the staves and broken view of the barrel showing the manner of inserting the staves; Fig. 3 is an enlarged broken cross-sectional view of two interlocked staves; Fig. 4 is an enlarged cross-sectional view of one of the staves; Fig. 5 is a broken sectional view of the end of one of the staves showing one of the slip joints and curved chime.

The barrel is built up of a series of interlocking staves 1, and, being all alike in construction, will, therefore, be designated by the same figure of reference. Each stave 20 is made of sheet metal having slip joints on each edge running the entire length of the stave. These joints are alike on each edge of all of the staves, but are offset in opposite directions as shown more clearly at Figs. 3 and 4. The joint *a* having an inward offset, and the joint *b*, on the opposite edge, an outward offset, thus locating the interlocking feature of the joints practically central with respect to the body portion of the staves. 40 Offsetting the joints (see Figs. 3 and 4), will form the abutting shoulders *a'* for the support of the straight portions *a*, while the inner ends of the return bends *a'* will abut against the inner walls *a* of the said straight portions, thus making a firm interlocking joint that can only be locked and unlocked by an endwise insertion of the staves. In Fig. 2 is shown the manner in which the staves are inserted, which view represents 50 the last stave being forced into position, in the direction of arrow *y* to complete the assembling of the staves to form the barrel.

The chimes are formed on each end of the staves by the outward curves *c*, as shown 55 more clearly at Fig. 5. The slip joints *a* and *b* stop at the base of the chimes, and the

width of the chimes is a trifle narrower than the stave so that when the barrel is set up the chimes will abut and present, practically, an unbroken and continuous circular edge at 60 the barrel's mouth.

The heads are formed of three sections as in an ordinary wooden barrel, viz.: the central section 2 and the outer segmental sections 3, and as such outer sections are exactly alike they will have the same figure of reference. The outer ends of the central section are provided with the curved lips *d* adapted to embrace and clasp over the chimes of the staves. On the upper surfaces of 70 these outer sections are the levers 6 pivotally supported on the studs 7. These levers have the recesses 6^a, and on each outer section are the studs 8 adapted to be clasped by these levers when the three sections are 75 together. In other words, the lever of one of the outer sections will register with the stud of the other section as shown at Fig. 1. When in this position, the brace or strut 9 of the central section will be swung around 80 on its pivotal support 10 to lock the levers 6 to the studs 8 as shown.

As each stave is a counter part of all the others as to contour, width and slip joints, they are readily interchangeable and either 85 end can be inserted when sliding the staves together in setting up the barrel. Each stave is curved longitudinally so that when the barrel is assembled it will have the same central pivotal point on which to roll as the 90 ordinary wooden barrel. Each stave is also provided with the longitudinal corrugations *j* for strength and support, and, as these corrugations rise above the outer surface, they 95 protect the interlocking joints when the barrel is being rolled on the ground. The central transverse or circularly arranged corrugations *k* at the highest point of the curve of the barrel will afford a bearing on which it will roll.

While I show the staves having the joint on one edge opening inward, and the same kind of a joint on the other edge opening outward, it will be understood that both joints on one stave could open inward, and both 105 joints of the stave interlocking therewith could open outward.

The overhanging lips of the head sections embracing as they do the extended outer curved chime *c* of the staves, will naturally 110 draw the ends of the barrel together, or, in other words, toward the center of the barrel

when the heads are locked, which arrangement will greatly strengthen the whole structure.

As the heads as well as the staves are interchangeable, the barrel can be taken down, reshipped in a small package and put together again at a very little expense.

Having thus described my invention, what I claim and desire to secure by Letters Patent is:-

1. A hoopless metallic bilge barrel comprising duplicate staves having their longitudinal edges provided with grooves and projections that extend longitudinally of said edges, the grooves and projections of adjoining staves being adapted to be interlocked by relative longitudinal movements of the staves, and heads engaging the ends of the staves.

2. A hoopless metallic knockdown bilge barrel comprising duplicate staves having their longitudinal edges shaped for interlocking engagement with adjoining staves, said staves being provided with external integral outwardly projecting ribs that parallel the longitudinal edges of the staves and prevent the joined portions of the staves contacting with the surface upon which the barrel rests, and means for closing the ends of the barrel.

3. A hoopless metallic knockdown bilge barrel comprising duplicate staves detachably connected at their longitudinal edges, each stave having outwardly projecting external integral ribs arranged in parallel rela-

tion to and adapted to shield the points of connection of the staves, said staves being provided with centrally disposed transversely extending external bearing ribs, and means for closing the ends of the barrel.

4. A hoopless metallic knockdown bilge barrel comprising duplicate staves having their longitudinal edges provided with return bends forming grooves and projections that extend longitudinally of said edges, said grooves being open at their ends to permit adjoining staves to be interlocked by alining the grooves and projections thereof and relatively moving the staves longitudinally, and closing means adapted to engage the ends of the staves.

5. A hoopless metallic knockdown bilge barrel comprising duplicate staves adapted for interengagement at their longitudinal edges by relative longitudinal movement of the staves, said staves having their ends outwardly curved to provide continuous chimes when the staves are assembled, and heads provided with flanges shaped complementally to and adapted for interlocking engagement with said chimes to retain the staves assembled.

Signed at Bridgeport in the county of Fairfield and State of Connecticut this 4th day of Jan. A. D. 1910.

HENRY A. HOWE.
